UNITED STATES PATENT OFFICE.

RICHARD McMILLAN, OF KINGSTON, ONTARIO, CANADA.

PIANO TUNING-PIN.

SPECIFICATION forming part of Letters Patent No. 345,711, dated July 20, 1886.

Application filed June 1, 1885. Serial No. 167,231. (No model.) Patented in Canada February 19, 1885, No. 21,118.

To all whom it may concern:

Be it known that I, RICHARD McMILLAN, of the city of Kingston, in the Province of Ontario, in the Dominion of Canada, have invented certain new and useful Improvements in Stringing Pianos; and I do hereby declare that the following is a full, clear, and exact description of the same, reference being had to the annexed drawings, in which—

10 Figure 1 is a plan of a portion of a piano-forte, showing my improved stringing. Fig. 2 is a vertical section of the same on line *x x*, Fig. 1. Fig. 3 is an independent elevation of the screw-follower. Figs. 4, 5, and 6 are de- 15 tail views of my improved wrest-pin.

My invention relates to improvements in that mode of stringing pianos in which the string is attached to a head or follower sliding in a screw-threaded hole in the wrest-plate, 20 and a tuning-screw depressing the follower to tighten the string; and the object of my invention is to obtain a delicate and accurate adjustment in tuning.

A is the sounding-board, B the piano-frame, 25 and C a strip inserted between the sounding-board and the metallic wrest-plate D, bolted to frame B, which plate D may be grooved at top to inlay a wire, E, on which the strings F bear. In the wrest-plate D are sunk holes 30 tapped with a screw-thread, each hole grooved longitudinally, the groove admitting the string F, and the hole receiving the adjusting or tuning screw I.

G is a follower attached to one end of the 35 string F, and is inserted in the screw-tapped hole and depressed therein slidingly by turning the tuning-screw I to give the required tension to the string in tuning.

To prevent the follower G from twisting or 40 turning, it is provided with a lug, H, at the side, to fit into the groove of the screw-threaded hole. The lug fills the groove accurately to prevent the follower turning by the frictional contact of the end of the adjusting-screw and 45 subsequent reaction by the strain of the wire. The lug also causes the follower to run smoothly and accurately in its hole without turning or twisting, and permits of a very delicate adjustment, so essential in tuning, and also is 50 convenient for fishing the follower out of its hole by a hooked wire inserted in the groove and catching the lug in case the string F should

break within the hole. The upper end of the follower is provided with a central indentation, and the tuning-screw I has a pointed end, 55 which centers in the indentation, so that the follower is prevented from wobbling and kept clear of catching in the screw-threads when rising by release of the tuning-screw I.

The exterior of the tuning-screws I is reduced and has a smooth shank, the terminations being formed tapering and four-square to receive the ordinary tuning-key. The reduced ends of the screws prevent the strings running from the back or top row from catching 65 in the screw-threads.

The followers G are transversely tapped with holes J K, the lower end notched to receive the string, and have a groove up the wall opposite to lug H, to intersect the holes, to prevent contact of the strings with the screw-threads in the hole in which the follower is placed, and preferably the upper hole intersects the indentation in the upper end of the follower. The end of the string is rove through 75 the upper hole in follower G, thence through the hole below, and thence lies in the groove in the wall and in the notch in the end of the follower, so that should a string break close to the follower the broken string will not unwind 80 and catch in the screw-threads, and thereby prevent the follower being drawn out of its hole.

I am aware that United States Patent No. 186,490 and British Patent No. 9,380 of 1884 85 show a means of stringing in which the wire is wound around a head or follower inserted in a screw-hole in the wrest-plate and a tuning-screw depressing the follower in the hole to strain the string; but practically such mode 90 is useless without my improvement, as tuning cannot be accurately performed.

I claim as my invention—

1. The combination, with the wrest-plate D, having a vertical screw-tapped hole grooved 95 longitudinally to receive a string, F, of the follower G, having a lug, H, fitting in the groove, string F, threaded through holes in the follower and passed under the notched end, and a tuning-screw, I, having a pointed end 100 fitting into a central indentation in the top of the follower, as and for the purposes set forth.

2. The combination, with the wrest-plate D, having a screw-threaded hole and a longi-

tudinal groove, of the follower G, having lug H, string F, and a tuning-screw, I, having a pointed end fitting into a corresponding indentation in the end of the follower, and the 5 shank reduced and provided with a tapering four-square head, as set forth.

3. The combination, with the string F, of the follower G, having a lug, H, and provided

with a conical indentation in the upper end, and the tuning-screw I, having a pointed end to matching the indentation, as set forth, for the purpose described.

RICHARD McMILLAN.
